United States Patent Office

Des. 187,305
Patented Feb. 23, 1960

187,305

WASTE CONTAINER

Felo Tocci, Leominster, Mass., assignor to Tucker Products Corporation, a corporation of Massachusetts

Application July 24, 1959, Serial No. 56,933

Term of patent 14 years

(Cl. D58—17)

I claim:

The ornamental design for a waste container, as shown.
